REINFORCED TOOL HANDLE

Filed July 9, 1926

INVENTOR
Joseph Kukla
BY *Soltan & Pleschka*
ATTORNEY

UNITED STATES PATENT OFFICE.

JOSEPH KUKLA, OF MONONGAH, WEST VIRGINIA.

REINFORCED TOOL HANDLE.

Application filed July 9, 1926. Serial No. 121,322.

This invention relates to reenforcing sleeves for the handles of hammers, axes and like implements, and its object is to provide an article of this character which shall serve 5 to prevent the fracture, or cracking of the handles to which it is applied.

The device is easily secured to the said handles, and is simple in construction and well adapted for economical manufacture.

10 In the following description and claim are set forth various other features of the sleeve and advantages to be obtained by its use, and the device in its simplest, as well as modified form is illustrated in the accompanying drawings, in which:

Fig. 1 shows the sleeve mounted on the handle of a sledge hammer.

Fig. 2 shows a section on the line 2—2 of Figure 1.

20 Fig. 3 shows the device in a modified form and secured to the handle of an axe.

Fig. 4 shows a section on the line 4—4 of Figure 3.

Fig. 5 is a sectional view taken on the line 25 5—5 of Fig. 3.

Referring more particularly to Figure 1 of the drawings, the sleeve 10 which may be constructed of seamless tubing, or welded, or otherwise joined at the side if preferred, is

30 mounted on the handle of a hammer, which comprises a handle 11 and a head 12. It is provided with V shaped openings at the sides, as shown at 13 which tend to break and distribute the vibration set up by the blows of 35 the head of the implement to which it is attached. In mounting it is forced back on the handle so that it binds firmly on the tapered portion and when set in position, it is secured at the large end by the pins as shown at 14 and

40 15. At the small end it is provided with teeth as shown at 16 and 17 which are forced into the handle and will effectually prevent any backward slip should the pins 14 and 15 become loosened by the recurrent vibrations.

45 In the form of the invention shown in Figure 3, the sleeve 10 is seen mounted on the handle of an axe. In this form it has a tapered slit 18 and is provided with a binding member 19 which is tapered in such a manner

50 that when forced over the sleeve it will draw the parts adjacent to the slit nearer together,

thus giving a close and strong grip on the handle. A rim 20 affords a bearing surface for driving the member into position. The teeth, as that shown at 21 are similar to those 55 illustrated in the preceding figures. As shown in Fig. 5, the teeth 21 are on the upper and lower ends of the sleeve 10 and are disposed downwardly so as to dig into the handle 11. The outermost sleeve 19 may be designed so as to apply a sufficient gripping 60 force on the inner sleeve 10 when the former is in the position shown in Figs. 4 and 5. In this position, the rim 20 of the outer sleeve 19 bears upon the end of the sleeve 10 and prevents displacement of the teeth 21. 65

While simple and efficient means are herein provided for the accomplishment of the objects of the invention and the elements shown and described are well adapted to serve 70 the purposes for which they are intended, it is to be understood that the invention is not limited narrowly to the construction illustrated in the drawings, but that minor alterations, and modifications may be made within 75 the scope of the appended claim.

Having thus described my invention, what I claim as new and desire to secure by Letters Patent, is as follows:

In a device of the class described, an implement handle comprising a tapered end, a tapered sleeve disposed on the tapered end of said handle having slits in the sides of the smaller end portion thereof, the tapered end of said handle being extended completely 80 through said sleeve and extending beyond the smaller end of the latter, teeth formed on the edge of the smaller extremity of said sleeve and disposed in advance of said edge portion and inwardly into the portion of said handle extending therebeyond, a telescoping tapered sleeve disposed over said first mentioned sleeve, and a rim on the smaller extremity of said telescoping sleeve positioned 85 in advance of the smaller extremity of said first mentioned sleeve engaging said handle and the teeth disposed therein for retaining 90 said teeth embedded in said handle. 95

In testimony whereof I have affixed my signature.

JOSEPH KUKLA.
